UNITED STATES PATENT OFFICE.

ARTHUR J. ADAMS, OF CHICAGO, ILLINOIS, ASSIGNOR TO FULTON MANUFACTURING COMPANY, OF CHICAGO, ILLINOIS, A CORPORATION OF ILLINOIS.

BABY-CARRIAGE.

No. 914,010.

Specification of Letters Patent.

Patented March 2, 1909.

Application filed August 6, 1906. Serial No. 329,386.

To all whom it may concern:

Be it known that I, ARTHUR J. ADAMS, a citizen of the United States, residing at Chicago, in the county of Cook and State of Illinois, have invented a new and useful Improvement in Baby-Carriages, of which the following is a specification.

My invention relates particularly to go-carts or folding baby carriages adapted particularly for use in traveling, owing to their capability of being folded compactly.

The present invention constitutes an improvement upon the baby carriage described and claimed in my Patent No. 789310, granted May 9, 1905.

My primary object is to provide improvements in the seat, back and foot-support of baby carriages.

The invention is illustrated in the accompanying drawings, in which—

Figure 1 is a side elevational view of a carriage constructed in accordance with my improvements, certain portions being broken away; Fig. 2, a broken perspective view illustrating the connection between one of the side flaps of the flexible back and the seat-supporting frame; Fig. 3, a broken perspective view illustrating a detail of the connection between a reversible boot or guard and an adjustable foot-rest; Fig. 4, a side elevational view of the carriage showing the back of the seat and the adjustable foot-support in different positions from those illustrated in Fig. 1; Fig. 5, a broken section taken as indicated at line 5 of Fig. 1 and showing a portion of the running-gear frame; Fig. 6, a broken, longitudinal section illustrating the adjustable foot-support in the same position as shown in Fig. 4, but with the reversible boot or guard in the position illustrated in Fig. 1; Fig. 7, a broken perspective view illustrating the manner of connecting the adjustable foot-support with the running-gear frame and with the seat-supporting frame; Fig. 8, a broken view partly in section, showing the reversible guard of the foot-support in the open position; and Fig. 9, a broken perspective view illustrating a portion of the link connections between the front edge of the seat and the seat-supporting frame.

In the preferred embodiment of the invention illustrated, A represents a running-gear frame equipped with hinged wheel-supports

A¹ provided with spindles upon which are journaled the wheels A²; B, a rearwardly inclined handle connected with the rear end of the frame A; C, a folding seat-support provided with means for maintaining its rigidity in use, said seat-support having pivotal connection at its front end with the front portion of the running-gear frame and pivotal connection at its rear end with the upper portion of the handle and being foldable upon itself and in relation to the running-gear frame in the manner described in said Patent No. 789,310; D, a seat equipped with a flexible back-D¹; and D², an adjustable foot-rest equipped with a reversible foot or foot-guard D³.

The running-gear frame, the wheel supports foldably connected therewith, and the folding seat-support C are fully described and claimed in the above-mentioned patent. It may be added, however, that the folding seat-support 'C' comprises foldable side-members c composed of upper and lower links 1 and 2 respectively, pivotally connected together at 3, the upper end of the link 1 being connected, by a pivot 4, with the adjacent handle-bar and the lower end of the link 2 being connected, by the pivot d³⁰, with the front portion of the corresponding side-member of the running-gear frame. The links 1 and 2 are releasably secured in the extended position by spring-held locking-devices 6, in a well understood manner.

The seat D is suspended between flexible side-members d which are connected at their lower edges with rods d¹ shown in Fig. 5 as extending parallel with the side-members a of the running-gear frame A, and said side-members d are connected at their upper edges with the foldable side-members c of the seat-supporting frame C.

The seat is shown, in Fig. 6, as comprising a board d² and a pad d³, with coverings of leather, or the like, d⁴, d⁵. At the front edge of the seat is formed a loop d⁶ which receives a transversely extending rod d⁷ provided at its ends with eyes d⁸ (Fig. 9) movable upon vertical links d¹⁰ whose upper ends are equipped with out-turned hooks d¹¹ which pass through eyes with which the side members c of the seat-supporting frame are provided, as shown in Fig. 4. The lower ends of the rods or links d¹⁰ are expanded and support washers d¹², which, in turn, support coil

springs d^{13} upon which the eyes d^8 of the transverse rod d^7 rest. Thus, the front edge of the seat is linked to the side members of the seat-supporting frame and is also spring supported. The flexible back D^1 comprises a lower section d^{14} and an upper section d^{15} . At the junction of said sections is provided a transverse loop d^{16} , and at the upper edge of the section d^{15} is provided a transverse 10 loop d^{17} . A rod d^{18} provided with down-turned ends d^{19} is employed; and when the back is in the extended reclining position shown in Fig. 1 the rod d^{18} passes through the loop d^{17} and its down-turned extremities 15 engage eyes d^{20} with which the side members b of the handle are provided, as more fully described in the above-mentioned patent. When the back is in the folded, more upright condition shown in Fig. 4, which corresponds 20 with the sitting posture of the child, the rod d^{18} passes through the loop d^{16} in a well-understood manner and engages eyes d^{21} with which the side-members c of the seat-supporting frame are provided, as more clearly shown in said patent. The back D^1 is provided with side flaps d^{22} which extend virtually the full length of both sections of the back. In the extended condition of the back, the flaps d^{22} are raised to 25 the position indicated in Fig. 1, and clamping hooks d^{23} which are provided at the free lateral edges of the flaps are caused to engage the side members c of the seat-supporting frame. In this position, the front margins d^{24} of the side flaps fit inside the rear margins d^{25} of the side members d . When it is desired to adjust the back to the position corresponding with the sitting posture, the flaps d^{22} are disengaged from the members c 30 of the seat-supporting frame and dropped downwardly and folded beneath the back, whereupon the upper section d^{15} of the back is folded downwardly upon the lower section, and buttons d^{26} with which the upper section 35 d^{15} of the back is equipped at its upper edge are caused to engage button sockets d^{27} with which the side flaps d^{22} are provided near their lower portions. In the meantime, or at any desired time, the rod d^{18} is removed 40 from the loop d^{17} , inserted in the loop d^{16} and caused to engage the eyes d^{21} of the side members c of the seat-supporting frame.

The foot-support D^2 comprises an adjustable frame d^{28} joined by pivots d^{29} to the 45 front portions of the members c of the seat-supporting frame near the front pivots d^{30} of said members; flexible material d^{31} joining the front edge of the seat D with a cross-rod d^{32} constituting the front end of the frame d^{28} , said flexible material having side flaps d^{33} joined at their upper edges to the side members of the frame d^{28} , thereby forming a chamber d^{34} for the child's feet; and a foot-board d^{35} contained in the bottom of said 50 chamber at a suitable inclination. The ad-

justable frame d^{28} comprises side members d^{36} whose front ends carry the cross-rod d^{32} ; links d^{37} joined to the rear downwardly curved ends of the links d^{36} and provided with slots d^{38} having offsets d^{39} at their upper ends affording locking shoulders d^{40} ; and a cross-rod d^{41} connecting the links d^{37} near their lower ends. The side members a of the running-gear frame are equipped with inwardly projecting studs d^{42} which engage the slots d^{38} . When the foot-rest frame d^{28} is raised to the position shown in Fig. 7, the weight of the rod d^{41} serves to cause the locking shoulders d^{40} to engage the studs d^{42} , whereby the frame is locked in its elevated position. When it is desired to release the frame in order to drop the foot-support to the position shown in Fig. 6, this is accomplished by raising the rod d^{41} , thereby freeing the links d^{37} from locking engagement with the studs d^{42} , permitting the foot-support to be dropped. 70 75 80 85

The boot, or guard, D^3 comprises flexible material d^{43} forming a continuation of the flexible material d^{31} , which in turn forms a 90 continuation of the flexible seat-covering d^4 , d^6 ; and a U-shaped frame member d^{44} (Fig. 8) which serves to give a rectangular outline to the body, of the guard. The boot is hinged on the transverse rod d^{32} which connects the side members or links d^{36} of the frame d^{28} . The boot body is provided at its ends with triangular flaps d^{45} provided with double buttons d^{46} adapted to engage sockets d^{47} with which the side members d^{36} of the frame d^{28} are provided at a distance from their front ends. The connection is illustrated in detail in Fig. 3; and from Figs. 1, 4, 6 and 8 it will be understood that the boot may be turned down and the flaps d^{45} connected with the members d^{36} of the frame d^{28} in one position, or the boot may be turned up and the flaps d^{45} connected with the members d^{36} of the foot-support frame in the reverse position. In Fig. 1, the full lines show 100 the boot in its up-turned position; and the dotted lines show the boot in its down-turned position, in which latter position the boot embraces the chamber d^{34} of the foot-support. 105 110 115

From the foregoing description, it will be understood that the back D^1 may be used in the inclined position shown in Fig. 1, or it may be used in the position corresponding with the sitting posture, as shown in Fig. 4. 120 The foot-support is ordinarily employed in the raised position when the back is in the inclined position shown in Fig. 1, and it may be employed in the raised position when the back is in the position shown in Fig. 4. The boot may be in the raised or operative position whenever so desired, and will serve as a means for tucking in robes, and may also serve as a means for carrying small parcels. When it is desired to leave the carriage in 125 130

such condition that the child may get out of it at will, the seat-support is dropped and the boot secured in the inoperative position.

The improvements may be applied to a carriage at small cost, and changes in adjustment may be quickly made, and the effect is to provide a go-cart of very great usefulness at very moderate cost.

The foregoing detailed description has been given for clearness of understanding only, and no undue limitation is to be understood therefrom.

What I regard as new, and desire to secure by Letters Patent, is—

1. In a baby carriage, the combination of a running-gear frame, a seat-supporting frame pivotally connected with the running-gear frame, a seat suspended on the seat-supporting frame, a foot-support frame pivotally connected with the seat-supporting frame, and means for locking the foot-support frame in the elevated position.

2. In a baby carriage, the combination of a running-gear frame, a seat-supporting frame pivotally connected therewith, a seat suspended on the seat-supporting frame, a foot-support frame pivotally connected with the seat-supporting frame and having members projecting in the rear of the pivotal connections, links pivotally connected with the ends of said members and provided with locking shoulders, and locking-shoulders carried by the running-gear frame and co-acting with said first-named locking shoulders, for the purpose set forth.

3. In a baby carriage, the combination of a running-gear frame, a seat-supporting frame pivotally connected therewith, a seat suspended on said seat-supporting frame, a foot-support pivoted on the seat-supporting frame and having members projecting in the rear of its pivotal support, links pivotally connected with said members and provided with locking shoulders, a cross-member connecting said links, and locking shoulders carried by the running-gear frame and coacting with the said first-named locking shoulders.

4. In a baby carriage, the combination of a running-gear frame, a handle pivotally connected with the rear portion thereof, a foldable seat-supporting frame pivotally joined at its rear end to the upper portion of the handle and pivotally joined at its front end to the front portion of the running-gear frame, a seat supported on said seat-supporting frame, a foot-support pivoted on said seat-supporting frame above the pivotal connection between the seat-supporting frame and running-gear frame, and means for locking the foot-support in the elevated position.

5. In a baby carriage, the combination with a running-gear frame having side members *a* equipped with inwardly projecting studs, and a seat-support having folding side members *c* pivotally joined at their front ends

with the front ends of the members *a*, of a foot-support comprising a frame having side members pivotally joined between their ends to the side members *c* and having a connecting member at their front ends, links pivotally connected with the rear ends of the side members of said foot-support frame and having slots engaging said studs, and a transverse member connecting said links.

6. In a baby-carriage, the combination of a running-gear frame, a seat, an adjustable foot-support chambered to receive the child's feet, and a reversible boot or foot-guard movably connected with said chambered foot-support.

7. In a baby carriage, the combination of a foot-support having a chamber for the child's feet, and a pivoted reversible guard having flaps reversibly connected with the foot support.

8. In a baby carriage, the combination of a foot-support comprising a frame, a chamber supported thereon, a pivoted reversible foot-guard, reversible flaps connected with the ends of said guard, and means for securing said flaps to the foot-support in both the operative and inoperative positions of the guard.

9. In a baby carriage, the combination of a running-gear frame, a handle, a seat-supporting frame, a seat, links pivotally connected with the seat-supporting frame and equipped with springs, means supported on said springs and supporting the front portion of the seat, and means supporting the rear portion of the seat.

10. In a baby carriage, the combination of a running-gear frame, a handle, a seat-supporting frame, links pivotally connected with the seat-supporting frame and equipped with springs, a transverse member supported on said springs, a seat having its front portion supported on said transverse member, and flexible means supporting the rear portion of the seat.

11. In a baby-carriage, the combination of a running-gear frame, a handle, a seat-supporting frame, a seat having its front portion connected with said seat-supporting frame, a flexible back connected with the rear portion of the seat, and side flaps connected with the flexible back and having edges extending substantially parallel with the side-members of the seat-supporting frame and equipped with means detachably engaging said side members.

12. In a baby carriage, the combination of a running-gear frame, a handle, a foldable seat-supporting frame comprising side members pivotally joined at their rear ends with the upper portion of said handle and pivotally joined at their front ends with the front portion of said running-gear frame, a seat, means suspending the front portion of said seat from said seat-supporting frame, a flexi-

ble back connected with the rear portion of the seat, means for connecting the upper edge of said flexible back with said handle, and side flaps connected with the flexible back and equipped at their free lateral edges with hooks clampingly engaging the side members of the seat-supporting frame.

13. The combination of a running-gear frame, a handle, a seat-supporting frame, a 10 foot-support frame having side members pivotally connected with the seat-supporting frame and equipped with button-sockets, and a foot-guard reversibly connected with the seat-supporting frame and equipped with 15 reversible flaps provided with double buttons adapted to engage said sockets, for the purpose set forth.

14. The combination of a horizontal running-gear frame, a seat-support foldable 20 substantially into the plane of the running-

gear frame, a seat suspended from said seat-support, a back, means for adjusting said back for a sitting posture and for a reclining posture, a foot-support frame, pivotal supports therefor, and independent means for 25 locking said foot-support frame when it is raised to an elevated position.

15. The combination with a horizontal running-gear frame, a seat-support foldable with relation to said frame, and a handle 30 adapted to fold forward onto said frame, of a foot-support frame, pivotal supports therefor, and means for effecting automatic locking of said foot-support frame when the same is raised to the elevated position.

ARTHUR J. ADAMS.

In presence of—
J. H. LANDES,
C. W. WASHBURN.
